BUILDING UNIT

John V. Patterson, Pittsburgh, Pa.

Application March 17, 1936, Serial No. 69,384

15 Claims.

(Cl. 189—1)

This invention relates to building units insulated to resist climatic conditions, and has for the primary object the provision of a pre-fabricated metallic device of the above stated character which may be manufactured and sold at a low cost and which may be easily and quickly assembled without the use of rivets or similar fasteners, the various parts being so constructed that they interlock to withstand maximum internal and external forces and strains and each part being of such weight that a single person, and not more than two persons, will be required in the handling thereof.

With these and other objects in view, this invention consists in certain novel features of construction, combination and arrangement of parts to be hereinafter more fully described and claimed.

For a complete understanding of my invention, reference is to be had to the following description and accompanying drawings, in which

Figure 1 is an end view illustrating a building constructed from fabricated parts constructed in accordance with my invention.

Figure 2 is a fragmentary horizontal sectional view showing the interlocking method of connection between the main floor beams and between the latter and pilasters.

Figure 3 is a sectional view taken on the line 3—3 of Figure 2 showing a pilaster as constructed of inner and outer members held assembled by ties and showing the connection between the pilaster and a floor beam and the latter resting upon a suitable foundation.

Figure 3a is a perspective view showing the inner member of a pilaster.

Figure 4 is a fragmentary perspective view partly in section showing the connection of longitudinally extending ties to a pilaster and the connection of the members of said pilaster.

Figure 5 is a perspective view illustrating one of the pilaster ties employed for connecting the inner and outer members of the pilaster.

Figure 5a is a perspective view illustrating a modified form of pilaster tie.

Figure 5b is a perspective view showing a floor plate.

Figure 6 is a perspective view showing one of the longitudinal ties employed for connecting the pilasters together.

Figure 6a is a fragmentary edge view showing a modified form of longitudinal pilaster tie.

Figure 7 is a fragmentary perspective view illustrating the inner member of a corner pilaster.

Figure 8 is a detail sectional view taken on the line 8—8 of Figure 3 showing insulation between the main floor beams.

Figure 9 is a fragmentary perspective view broken away showing the connection between a main floor beam and a pilaster.

Figure 10 is a detail sectional view showing a tie beam between the floor and ceiling beams.

Figure 11 is a fragmentary view showing the tie beam between the floor and ceiling beams and looking at said tie from right angles to that shown in Figure 10.

Figure 12 is a detail sectional view of a modification showing the connection of the wall veneering to the pilasters.

Figure 13 is a fragmentary perspective view partly in section showing means for anchoring partition pilasters to the main beams.

Figure 14 is a perspective view showing a modified form of means for securing pilasters to the main beams.

Figure 15 is a view similar to Figure 14 showing a modified form of securing means.

Figure 16 is a fragmentary perspective view showing the connection of a horizontal tie beam to main beams.

Figure 17 is a fragmentary sectional view showing the mounting of the roof to the wall construction without the use of rivets, bolts or like fasteners.

Figure 18 is a fragmentary perspective view partly in section showing the anchoring of a roof rafter to a ceiling beam.

Figure 19 is a sectional view taken on the line 19—19 of Figure 17.

Figure 20 is a fragmentary perspective view illustrating one of the roof rafters, or box channel beams.

Figure 21 is a sectional view taken on the line 21—21 of Figure 17.

Figure 22 is a sectional view taken on the line 22—22 of Figure 17.

Figure 23 is a sectional view taken on the line 23—23 of Figure 17.

Figure 24 is a perspective view showing a tie employed between a main beam and a roof rafter.

Figure 25 is a fragmentary perspective view illustrating a ridge cap for the roof.

Figure 26 is a fragmentary perspective view showing one of the tie braces employed between the roof rafters and the ceiling beams.

Figure 27 is a fragmentary perspective view showing a companion tie brace to the tie brace shown in Figure 26.

Figure 28 is a fragmentary perspective view showing the mounting of shingles to the roof rafters.

Figure 29 is a sectional view taken on the line 29—29 of Figure 28.

Figure 30 is a sectional view taken on the line 30—30 of Figure 28.

Figure 31 is a perspective view illustrating one of the shingles.

Figure 32 is a fragmentary perspective view showing an anchoring element employed for locking shingles together and to the roof rafters.

Figure 33 is a horizontal section showing a detail of a modified form of structure for connecting wall plate members to the stud upright or pilaster members.

5 Figure 34 is a perspective view showing a detail of an element employed in the embodiment of Figure 33.

Referring in detail to the drawings, the numeral 1 indicates a building or dwelling assembled from fabricated units and members forming the subject matter of the present invention. Any suitable type of foundation 2 is provided for the building or dwelling 1 to rest upon and the latter may have insulated walls, flooring and ceiling to 15 resist weather elements. Any suitable insulation 3 is employed. The vertical walls as well as interior partitions of the building or dwelling 1 include spaced pilasters or stud uprights 4 and 5. The pilasters 5 are employed at the corners of 20 the walls and are somewhat shaped differently from the pilasters 4. The ceilings and floors of the building or dwelling 1 are supported by main channel beams 6 interlocked with the pilasters 4. Certain of the main beams 6 are connected to the 25 corner pilasters 5 by tie beams 7. Tie beams 8 are employed between certain of the main beams 6 and certain of the pilasters 4 and may project beyond the outer walls of the building or dwelling for the purpose of supporting a porch or like 30 construction (not shown). The tie beams 8 are arranged at right angles to the main beams 6 and the latter are further braced by spacers 9. When I mention "pilasters" in the specification and claims, I have reference to stud uprights or 35 similar members.

The pilasters 4 and 5 heretofore referred to, each include inner and outer members 10 and 11, both of hollow formation and of substantially rectangular shape in cross section. Throats or 40 slots 12 are provided in the members 11 and 10 and extend the full length thereof. The throats or slots 12 are bordered by spaced flanges 13. The members 10 and 11 when assembled to provide pilasters have the throats 12 in opposed relation. The throats receive ends of perforated 45 pilaster ties 14 each of substantially I beam construction. The ties 14 are assembled in the members 10 and 11 from the ends of the latter and act to retain the members 10 and 11 in proper 50 relation to one another. The pilasters are connected by longitudinally extending pilaster ties 15. The ties 15 are arranged to connect together the inner members 10 of the pilasters as well as the outer members 11. Figure 4 shows clearly 55 how the ties 14 and 15 are applied to the members 10 and 11 of the pilasters. The ends of the ties 15 are of angle iron shape so as to extend through the throats 12 of the members 10 and 11 and contact with the inner walls thereof. The ties 15 are applied to the pilasters from the ends 60 of the latter. The ties 14 may be substituted for by perforated ties 17, as shown in Figure 5a. The ties 17 consist of an elongated strip having 65 angularly related ends 18 fitting in the members 10 and 11 of the pilasters by way of the throats and said strips are provided with shoulders or flanges 19 adapted to abut the flanges 13 of the members 10 and 11. The ties 17 are applied to 70 the pilasters endwise of the latter. The ties 14 and 15 when applied to the members 10 and 11 of the pilasters rest one upon the other thereby providing a rigid construction eliminating the use of rivets or like fastening means for connecting 75 the pilasters together and each is provided with

a ribbed apron 16. The aprons overlap to provide backing for wall insulation to engage.

Each main floor or ceiling beam 6 consists of companion sections 20 of channel iron construction arranged back to back with a limited space 8 20a between said sections. The sections at the ends thereof are cut away and bent to form attaching flanges 21. The attaching flanges 21 of one section extend in an opposite direction to the attaching flanges of the other section. The flanges 10 21 and cutaway ends of the section of the main beam slide into the outer members of the pilasters from an endwise direction with respect to the latter. The main beams 6 are connected to the outer members 11 of the pilasters while the inner 15 members rest upon the main beams with extensions 21a thereof extending into the spaces 20a. The outer members 11 are of a slightly greater length than the inner members, this being clearly shown in Figure 3. The connections of the main 20 floor and ceiling beams to the pilasters 4 are identical and the main ceiling beams are applied to the pilasters after the uppermost ties 14 and 15 have been applied to said pilasters.

The main floor beams are applied to the foundation during the making of the latter so that after the completion of said foundation the material thereof extends through the spaces 20a between the main beams and into the outer members 10 of the pilasters, and have the extensions 21a of the inner members embedded therein, thereby firmly anchoring said parts to the foundation. A suitable flooring is supported by floor plates 22a and the latter are mounted on the main floor beams. Each floor plate 22a has a 35 flange 23a at one end and spaced ears 24a at the opposite end and engage the floor beams, as shown in Figure 8. The spacers 9 heretofore referred to each have angularly related feet 22 to abut the beams 6. The tie beams 8 are constructed similarly to the main beams 6 but of shorter length and each have one end cut away to form attaching ears 23 received in the spaces between the sections 20 of the main beams. The ears 23 are of angular formation so that besides 40 passing between the sections 20 of the main beams they also rest upon the upper edge of one of the sections 20 while the lower edges of the sections of the tie beams rest on the lower edges or flanges of the sections 20 of the main beams. 45 The other ends of the sections of the tie beams 8 are shaped to fit in the members 10 and 11 of the pilasters 4.

The pilasters 5 include the inner and outer members similar in construction to the inner and 55 outer members of the pilasters 4 except that the outer members of the pilasters 5 have faces A arranged at right angles to one another to conform or go to make up the corner of adjacent walls of the building or dwelling. The inner 60 member of each pilaster 5 has a straight face B and angularly related faces C. The ties employed between the members of the pilasters 5 have their ends shaped to conform to the contour of the walls of the inner and outer members of 65 said pilasters 5. The braces 7 extend between the inner members of the pilasters 5 and certain of the main beams 6. One end of each brace 7 is equipped with the attaching ears 23 so as to hook 70 into the main beams 6.

The pilasters employed in the construction of 75 partition walls for the building or dwelling 1 rest upon the main beams 6 of the floor and against the main beams of the ceiling and are tied to said main beams by clips 25. Each clip is of

substantially U-shaped formation to receive therein the members 10 and 11 of the pilasters and have frictional contact therewith and are provided with tongues 26 extending between the 5 sections of the main beams. The clip 25, as shown in Figure 13, is constructed from a single length of material. However, clips may be made, as shown in Figures 14 and 15 wherein the 10 tongues are separable from the U-shaped portions. The difference between the form of clips shown in Figure 14 and that shown in Figure 15 is that the tongues are arranged at different 15 angles with respect to the U-shaped portions, this permits the securing of partition pilasters to the 20 main beams either longitudinally or transversely thereof.

Vertical tie beams 26' may be arranged between the main ceiling and floor beams 6 and each are composed of a pair of sections and each section 0 of channel iron construction with their ends cut to form anchoring extensions 27 arranged to enter the spaces between the sections 20 of the main beams 6. The tie beams 26 are principally employed for supporting door and window frames.

Sheets of inner and outer wall coverings 28 and 29 are adapted to the pilasters 4 and 5 and may be in the form to represent brick walls on the outer wall construction and plastering on the inner wall construction or other veneer effects 5 may be had. The sheets have edges thereof cut away to form anchoring portions 30 engageable with the members of the pilasters and the ties 15. The sheets are applied to the pilasters endwise of the latter during the assembling of the building 20 or dwelling.

In the embodiment of my invention shown in Figure 12, outer facing plates or wall panels 28a have been employed instead of the wall covering construction 28 and 29 of Figure 2. The plates 28a preferably interlock with the pilasters or studs 4 and the ties 15; they have angularly-offset end portions of L shape. The feet of the angle portions are lapped or folded over to strengthen the construction and to tightly interlock with adjacent portions of studs 4 and ties 15. As seen, the facing or finish plates 28a can be moved obliquely into position after the members 4 and 15 have been properly associated or interengaged. The studs 4 act as joint finish 25 members in the arrangement of Figure 12.

A gable type roof 31 is shown as applied to the walls of the building or dwelling and includes relatively spaced roof rafters 32 each of substantially rectangular shape in cross section and each 5 provided with a slot 33 extending the full length thereof and in the upper face. The lower faces of the rafters have spaced slots 34 to receive T-shaped ties 35 which ties extend through the spaces 20a defined by the sections 20 of the ceiling beams and have the ends thereof bent to engage with the flanges of said sections, as clearly 10 shown in Figure 18, thereby effectively anchoring the roof rafters to the ceiling beams. The rafters are further connected to the ceiling beams by diagonally arranged braces 34' arranged in pairs, one brace of each pair straddling the companion brace, the latter having spaced shoulders 35' thereon to abut edges of the companion braces. One end of each brace has anchoring ears 36, 15 see Figure 26, to engage in the rafters while the opposite end of each brace extends through the space 20a defined by the sections 20 of the ceiling beam and is bent sufficiently to cooperate with shoulders 37 in anchoring the brace to the ceiling 20 beam.

Steel shingles 38 can be applied to the roof rafters and each is equipped with retaining or locking flanges 39 adapted to enter the slots 33 of said rafters by sliding said shingles endwise of the rafters during the application of the shingles 5 to the rafters. The shingles overlap one another and their side edges are arranged in abutting engagement. Any suitable roofing material or paint may be employed for closing the seams between the shingles. The flanges 39 of the shingles have 10 applied thereto locking strips 40 so that each shingle will be joined to the adjacent shingle at the longitudinal edges of said shingles and within the roof rafters. The locking strips 40 also act to close the slots in the rafters 33 and are applied to the rafters endwise. The roof rafters at their lower ends may have ears or extensions thereon to engage with the lowermost shingles thereby effectively retaining the shingles assembled on the rafters in roofing formation (not 15 shown). A ridge strip 41 is applied to the upper ends of the roof rafters and partly overlies the upper rows of shingles.

The roof rafters may be connected in oppositely arranged pairs by braces 42 cooperating with the braces 34' in providing a rigid roof construction capable of withstanding maximum internal or external forces.

Ceiling material may engage with the ceiling beams 6 and may be secured to the inner members 10 of the pilasters (not shown) similarly to the securing of the wall coverings to said pilasters.

The ends of the longitudinally extending pilaster ties may be shaped or constructed, as shown at 43, in Figure 6a. The ends 43 bring the major portions of the ties 15 in close abutting engagement with the members of the pilasters.

All of the parts heretofore referred to are of a metallic material and the weight of each part is such that a person may readily handle the same 40 for the purpose of assembling the building or dwelling. Further, it is to be noted that all parts are effectively interlocked with one another so as to eliminate rivets, bolts or similar fasteners and will provide a durable and rigid construction capable of withstanding maximum internal and external forces. Further, the interlocking connections between the parts permit the structure to be easily and quickly assembled and further permits the parts to be manufactured and shipped 45 to selected destinations to be assembled or put together in building or dwelling structure by either skilled or unskilled labor.

Having described the invention, I claim:

1. A fabricated building comprising pilasters, means tying said pilasters together and having interlocking connections therewith, floor and ceiling beams interlocked with said pilasters and each including spaced companion sections, said floor beams supporting said pilasters on a foundation with said pilasters protruding between the companion sections thereof to anchor said sections and the pilasters to the foundation, wall constructions supported by the pilasters, and a roof secured to the ceiling beams.

2. A fabricated building construction comprising pilasters each including spaced members each of channel construction, tie means interlocking with said members of each pilaster, tie means arranged to interlock with inner wall portions of 60 said channel members of said pilasters and to connect the pilasters, and floor and ceiling beams interlocked with the pilasters.

3. A fabricated building construction comprising pilasters each including inner and outer mem- 75

- bers of channel construction defining slots therein, tie means extending into the slots of the members for connecting said members of each pilaster in spaced relation, tie means extending into the slots of and interlocking with the members of the pilasters and arranged longitudinally to connect one pilaster to another, and floor and ceiling beams interlocked with the pilasters.
4. A fabricated building structure comprising 10 pilasters each including inner and outer channel members defining therein slots, tie elements extending into the slots of the members of the pilasters, and interlocking therewith to retain the members of the pilasters in spaced relation, 15 longitudinally extending pilaster ties extending into the slots of said channel members and connecting the inner members thereof together and the outer members thereof together, and ceiling and floor beams interlocking with the pilasters.
- 20 5. A fabricated building structure comprising pilasters each including inner and outer members of channel formation, ties of I beam construction interlocking with the members of the pilasters to join the members of each pilaster together in spaced relation, longitudinally extending ties having hook-shaped ends interlocking with the members of the pilasters, and ceiling and floor beams interlocking with the pilasters with the floor beams supporting said pilasters 25 and the latter supporting the ceiling beams.
- 30 6. A fabricated building structure comprising pilasters each including inner and outer channel members, floor and ceiling beams each including companion sections having the ends of said sections cut away to form attaching flanges interlocking with the members of the pilasters, tie means between the members of each pilaster, and tie means between the inner members of the pilasters and between the outer members of said pilasters.
- 40 7. A fabricated building structure comprising pilasters each including inner and outer channel members, floor and ceiling beams each including companion sections having the ends of said sections cut away to form attaching flanges interlocking with the members of the pilasters, tie means between the members of each pilaster, tie means between the inner members of the pilasters and between the outer members of said pilasters, and bracing beams interlocking with certain of said floor and ceiling beams and with certain of said pilasters.
- 45 8. A fabricated building structure comprising pilasters each including inner and outer channel members, floor and ceiling beams each including companion sections having the ends of said sections cut away to form attaching flanges interlocking with the members of the pilasters, tie means between the members of each pilaster, tie means between the inner members of the pilasters and between the outer members of said pilasters, bracing beams interlocking with certain of said floor and ceiling beams and with certain of said pilasters, and spacers engaging certain of said floor and ceiling beams.
- 50 65 9. A fabricated building structure comprising pilasters each including inner and outer channel members, floor and ceiling beams each including companion sections having the ends of said sections cut away to form attaching flanges interlocking with the members of the pilasters, tie means between the members of each pilaster, tie means between the inner members of the pilasters and between the outer members of said pilasters, bracing beams interlocking with certain of said floor and ceiling beams and with certain of said pilasters, and spacers engaging certain of said floor and ceiling beams.
- 60 70 10. In a fabricated building construction, a stud upright having spaced-apart channel-like portions, a beam, an element interlocking with the spaced-apart portions of said stud upright and with said beam for holding them in position with respect to each other, and a tie member extending into and interlocking with the spaced-apart channel-like portions of said stud upright. 1
11. In a fabricated building construction, a stud upright, a beam, said stud upright having spaced-apart portions, said beam having a pair of channels in a substantially back-to-back relationship, and an element interlocking with the spaced-apart portions of said stud upright and arranged to fit between the backs of said pair of channels for holding said stud upright and said beam in position with respect to each other. 2
12. In a fabricated building construction, a stud upright, a beam, said stud upright having spaced-apart portions, said beam having spaced-apart web portions, and an element interlocking with said spaced-apart portions of said stud and web portions of said beam for holding them in position with respect to each other. 3
13. In a fabricated building construction, spaced stud uprights, a wall plate member adapted to extend longitudinally between an adjacent pair of spaced stud uprights, and a tie element extending longitudinally between a pair of spaced apart stud uprights, said tie element connecting said plate member to said pair of studs, said plate member having an offset portion extending between portions of said tie element member and a stud of the pair and holding said plate member in position with respect to such stud. 4
14. In a fabricated building construction, beam members having spaced-apart portions, spaced-apart stud uprights having spaced-apart portions, an element cooperating with the spaced-apart portions of said beam members and said stud uprights, wall plate members extending between spaced-apart stud uprights, longitudinal tie members connecting said stud and plate members, said plate members having offset portions extending between portions of said tie members and said studs for holding said members in position with respect to each other. 5
15. In a fabricated building construction, beam members having spaced-apart portions, spaced-apart stud uprights having spaced-apart portions, an element cooperating with the spaced-apart portions of said beam members and said stud uprights and holding them in a locked position with respect to each other, wall plate members extending between said stud uprights, longitudinal tie members connecting said studs and said plate members, said plate members having offset portions extending between portions of said tie members and studs for holding said members in position with respect to each other, and a transverse member extending between said spaced-apart portions of said stud uprights and interlocking therewith. 6

JOHN V. PATTERSON.
